CLAIM

The ornamental design for a heart bottle, as shown and described.

DESCRIPTION

FIG. 1 is a perspective view of a bottle showing our new design;

FIG. 2 is a front plan view thereof;

FIG. 3 is a right side view of the design of FIG. 2;

FIG. 4 is a back plan view of the design of FIG. 2;

FIG. 5 is a left side view of the design of FIG. 2;

FIG. 6 is a top plan view of the design of FIG. 2; and,

FIG. 7 is a bottom plan view of the design of FIG. 2.

The broken lines shown in all figures are for illustrative purposes only and form no part of the claimed design.
